UNITED STATES PATENT OFFICE.

CARL C. CHASE, OF NEW YORK, N. Y., ASSIGNOR TO MOTOR RECORDING CORPORATION,
OF NEW YORK, N. Y., A CORPORATION OF DELAWARE.

ABSTRACT OF TITLE FOR MOTOR VEHICLES.

1,419,020.

Specification of Letters Patent. Patented June 6, 1922.

Application filed May 20, 1921. Serial No. 471,085.

To all whom it may concern:

Be it known that I, CARL C. CHASE, a citizen of the United States, and resident of New York city, in the county of New York and State of New York, have invented certain new and useful Improvements in Abstracts of Title for Motor Vehicles, of which the following is a specification.

My invention relates to means for safe-guarding motor vehicles against theft, and is particularly directed to an improved combination and arrangement of documentary forms adapted to enable the owner of a motor vehicle to prove readily his right thereto.

Under present conditions, the purchaser of a used motor vehicle is unable to obtain conclusive proof that the vehicle has not been stolen, and is therefore compelled to run the risk of losing the vehicle to a former owner from whom it was illegally obtained.

A primary object of my invention is to provide means whereby the purchaser may obtain satisfactory evidence of the vendor's title, thereby practically eliminating the above-mentioned risk. Obviously, this arrangement is calculated to reduce to a minimum the theft of motor vehicles, owing to the practical impossibility for a thief to obtain the documents necessary, in accordance with my invention, to prove title to the purchaser. A corollary object, therefore, is to prevent the theft of motor vehicles by radically increasing the difficulty of disposing of such vehicles.

Another object is to provide a composite document which may be permanently retained by the successive owners of a motor vehicle, the document forming an abstract of title thereof and furnishing on its face the evidence necessary to prove to a prospective purchaser the vendor's right to sell the vehicle.

I have also provided means whereby the owner of the vehicle may notify a central office of the company issuing the abstract of any sale, lien or other transaction affecting title to the vehicle; and I may furthermore provide means whereby such company, after investigating the transaction of which it is apprised, may enter or have entered upon the abstract its verification of the transaction serving as evidence to future purchasers that the transaction is as represented on the abstract. This arrangement also permits the central office of the issuing

company to keep a permanent record of the various transactions affecting the vehicle, so that any alteration of the abstract can readily be detected, and lost or mutilated abstracts can be replaced.

Other objects and advantages of my invention will be apparent from the following description, taken in connection with the accompanying drawings, in which:

Fig. 1 is a front view of one form of abstract with the cover turned back to expose the first page, parts of the various sheets being broken away to expose the underlying sheets, 65

Fig. 2 is a plan view of the back of the first page, 70

Fig. 3 is a plan view of a page of lien and lien discharge notices,

Fig. 4 is a plan view of a form of certificate of ownership, 75

Fig. 5 is a fragmentary plan view of a portion of the duplicate bill of sale sheet, and

Fig. 6 is a fragmentary view of a record and memorandum sheet, 80

Before setting forth the details of my invention, I will outline the general features of the system in which my invention is intended to be used, so that such details may be more thoroughly comprehended. Upon application of an owner of a motor vehicle an abstract will be issued to the owner by the title company, after suitable investigation, describing the motor vehicle in sufficient detail for identification, and containing a suitable certificate as to the rights of the owner. It may be stated here that my invention is adapted either for the insurance of title to motor vehicles or for the registration or recording of ownership, without insurance; but for convenience the forms herein disclosed are those adapted to the latter system.

When the owner wishes to sell his motor vehicle, he displays to the purchaser his abstract of title as evidence of ownership; and if the purchaser desires to continue the abstract service, a record of the sale is made in the abstract on a blank form provided therein, and also on a separate form which is forwarded to the issuing company. After proper investigation the transfer is ratified by the company and a suitable record of this fact is preferably inserted in or attached to the abstract. In the precise form 110

of the system disclosed herein, the company at this stage forwards to the new owner a certificate adapted to be attached to the last record of sale, the certificate stating the extent of the company's ratification of the transaction. Suitable forms are provided for a series of sales, so that the abstract, if successive owners utilize the service, presents a continuous chain of title together with suitable verification of individual transactions by the company.

Provision may also be made for entering on the abstract any transactions of importance to the title or possession of the vehicle, such as liens, change of numbered parts, or the like; and in the preferred form suitable blank spaces are provided on the back of each sales record, so that the purchaser can ascertain, by an inspection of the back of the record of sale to him, exactly what encumbrances or alterations the vehicle has been subjected to up to the time of purchase by him. A similar record may be made on the back of the sales record sent to the company, so that the company may enter on its records the transactions affecting title or possession which are noted on the abstract. In furtherance of this system, blanks may be provided in the abstract for notifying the company when a lien is placed on the vehicle, this process assuring the mortgagee that any purchaser utilizing the abstract service will be duly notified of the existence of such a lien. Complementary lien discharge notices may also be provided for notifying the company in similar manner when a lien has been discharged, the signature of the mortgagee on such notice serving as verification of its authenticity.

Up to this point I have referred to records of sales as being included among the forms embodied in the abstract. I have found it highly useful to employ as such record a formal bill of sale, one copy of which is retained in the abstract, and the other, signed in duplicate, is forwarded to the company. In addition to the convenience which this system affords for facilitating the transfer of motor vehicles in due legal form, the duplicate bill of sale may also be forwarded by the company to the secretary of state or other proper officer having jurisdiction over motor vehicles, for entering on his records. It will be apparent that this arrangement serves the double purpose of additionally safeguarding purchasers, and of insuring the compliance with technical requirements of law relating to transfers of motor vehicles.

Coming now to the details of the specific form of abstract shown in the drawings, which as above noted is based upon the theory of registration of title rather than upon the basis of insurance, Fig. 1 shows a form of abstract which has been found thoroughly useful and convenient in practice.

This abstract consists of sheets 10, 11, 12, 13, 14 and 15, together with the front cover 16 and the back cover 17, the latter preferably being relatively heavy to protect the abstract throughout the years of hard usage to which it may be subjected. The first sheet 10 has imprinted upon the front page thereof a certificate of ownership 18, and a detailed description 19 of important features of the motor vehicle, which may be embodied in the certificate of ownership.

Where an insurance system is employed, this certificate may be in the form of an insurance guarantee; but in the form shown it is in the nature of a certificate that the owner has warranted to the issuing company that he has a right to possession of the motor vehicle, and that it is free from encumbrances except as stated. Obviously, a great variety of other forms of certificate may be substituted for this one, depending upon the general business scheme which is followed, without affecting the organization of documents in the abstract which constitutes my invention.

Below the certificate of ownership are the forms on which the successive sales are entered. In the arrangement shown, these forms consist of bills of sale 20 and 21, each being in any desired form and preferably including an acknowledgement. The bills also should contain a reference to the abstract and to the liens and encumbrances mentioned therein, if any, so that the abstract is in substance embodied in the contract, an important feature from a legal point of view. The bills of sale are numbered successively, and are permanently bound in the abstract.

The back page of sheet 10 is shown in Fig. 2. This is divided into a series of forms 22, 23 and 24, each located on the back of one of the forms on the front of said sheet. These forms are so arranged that the owner of the motor vehicle can enter thereon details of transactions affecting the title, possession or condition of the vehicle; so that each purchaser will have a record on the back of his particular bill of sale or sales record, of such transactions. The forms shown in Fig. 2 are each divided into two portions, one being adapted for the entry of liens and the other for the entry of numbered parts which are replaced.

In Fig. 3 are shown specimens of one type of notice which may be employed in connection with the imposition and discharge of liens. These notices are detachable, and are successively numbered so that they may be removed and forwarded to the issuing company as liens are imposed or discharged. In the particular arrangement disclosed, lien notices 25, 26 and 27 are vertically aligned on the left half of the sheet, which in the arrangement of Fig. 1 is sheet 14; and the notices are preferably rendered sepa-

able from the sheet without difficulty by means of lines or perforations or incisions 28^a. A corresponding series of lien discharge notices 28, 29 and 30 are imprinted on the right-hand half of the sheet and are similarly detachable. The notices may be numbered serially from bottom to top of the sheet for convenience in detaching them in order; and a second sheet 15 of such notices 10 may be employed, similar in every way to that of Fig. 3, except that the numbers of the notices on sheet 15 are in sequence to those on sheet 14.

Duplicate records of sales are preferably embodied directly in the abstract, this being accomplished in the form shown by employing a sheet 11 which may be an exact duplicate of sheet 10, both as to the front and rear pages of said sheet, except for certain changes indicated in Fig. 5. For one thing, the bills of sale or other records contained on the front of sheet 11 may be marked "duplicate" as in the bill of sale 31 shown in Fig. 5. Furthermore, it has been found highly advantageous from a legal point of view to embody in the duplicate bill of sale, which is forwarded to the issuing company, a warranty on the part of the purchaser requesting the continuance of abstract service, or by the vendor, to the effect that the vehicle is free from encumbrances except as stated on the rear of the duplicate bill of sale carrying the warranty. By this method, the company is in possession of a warranty as to encumbrances on the vehicle which will enable it, and those employing its service, to recover damages from any purchaser or vendor making false entries as to encumbrances or other transactions affecting the title or condition of the vehicle.

It is of course understood that the duplicate bills of sale or other sales records carried by sheet 11 are detachable therefrom, as by employing suitable lines of perforations 32 between the various instruments on sheet 11. While I have described sheet 11 as being a substantial duplication of sheet 10, and while this has been found useful in practice, it will be readily understood that my invention is in no respect confined to this particular arrangement. For example, the two sales records need not necessarily be substantial duplicates of each other, nor need they both consist of bills of sale in the broadest phase of my invention. Furthermore, the specific warranty 33 may be embodied in any suitable form, and need not be separate from the rest of the bill of sale or sales record, although this form is shown in Fig. 5.

The certificate of ownership 34 which is issued to subsequent owners is shown in Fig. 4. This certificate forms in effect a part of the abstract, and under the scheme of doing business heretofore outlined, I have

found it convenient to employ a certificate adapted to be attached physically to the abstract, rather than one permanently bound in the abstract, as the latter arrangement entails some practical difficulties of a business nature. I have therefore provided this certificate with a marginal stripe of adhesive 35, and have formed on the original bills of sale 20 and 21 a suitable marginal space 36 to which the certificate may be affixed by means of the adhesive, without obscuring the sales record. It will be apparent, however, that a great many different methods of embodying the certificate in the abstract can be substituted for the one disclosed.

The certificate 34 is governed as to its form by the extent to which the issuing company protects the owner. The form shown is in substance a certificate as to the company records and the warranty of the preceding owner, being part of a recording system rather than an insurance system, as heretofore indicated. However, the certificate might with equal facility be adapted to an insurance scheme.

If desired a suitable blank form 37 shown in Fig. 6 may be employed for a record of insurance, and a form 38 for a record of miscellaneous transactions, the abstract shown in Fig. 1 having these forms located on the back of the cover 16.

While the general scheme of business has heretofore been set forth, the precise method of manipulating the specific form shown will be reviewed to insure clarity. When a motor vehicle owner applies for an abstract, he files a suitable application; and upon investigation an abstract is sent to him with the certificate of ownership 18 suitably filled out and signed. Upon placing any lien on the car, lien notice 25 is filled out, signed by the mortgagor and mortgagee, and mailed to the company. An entry of the lien is also made in the suitable space in the blank record 23 on both sheet 10 and sheet 11. On discharging such lien, the discharge notice 28 is detached and forwarded to the company, and a suitable notation is made on the forms 23.

When any numbered part of the vehicle is replaced, that fact is also entered on both forms 23; as otherwise the purchaser, comparing the numbers of the various parts with those on the certificate of ownership record section 19, would refuse purchase because of the discrepancy.

When the motor vehicle is to be sold, bill of sale No. 1, indicated by numeral 20 in Fig. 1, and the duplicate bill of sale No. 1, (31 in Fig. 5) are both filled out and signed by both parties, acknowledged by them before a notary public, and the warranty 33 is signed by the vendee, and if considered desirable, by the vendor. The duplicate bill of sale 31 is then detached and sent to the company. After checking up the various

features of the transaction, which may include suitable investigation in the office of the Secretary of State, the certificate shown in Fig. 4 is properly filled out and executed, and is forwarded to the purchaser, who pastes it over bill of sale No. 1 (20 in Fig. 1). The transaction is now complete, and the new owner follows the same procedure.

- 10 It will be apparent that the adoption of my invention will increase so greatly the difficulties attendant upon the sale of stolen motor vehicles that it is believed that such thefts will be reduced to a minimum; and 15 my invention furthermore provides prospective purchasers with an effective and practical means of protection against the purchase of motor vehicles which have been stolen or upon which undisclosed liens have 20 been placed.

It is believed that eventually a comprehensive system for the compulsory recording of encumbrances on motor vehicles will be adopted in all States; and further, that 25 various State laws effecting systems of insurance will be altered to permit greater latitude in the insurance of purchasers of motor vehicles than is possible under the laws and recording systems now in existence. 30 My invention will be equally applicable to such improved conditions. However, the particular arrangement shown has been calculated to meet numerous difficulties in the present legal situation; and the solution of 35 these difficulties by the devising of a practicable arrangement and combination of forms in the abstract has been an important object of my invention.

While I have indicated the principal features of my invention and in connection with the detailed description have shown where various modifications may be made, it will be apparent that a number of other changes and variations can readily be employed within 45 in the scope of my invention; and I do not consider such invention to be limited to the disclosure herein, its true scope being indicated by the following claims.

While I have used the expression "title 50 certificate" or "certificate of title" in the claims for convenience, it will be understood that these expressions are not limited to the type of certificate shown in the illustrations, but are intended to refer generically to all 55 certificates containing a statement of the issuing company bearing upon a right to possession or ownership, whether the certificate forms a part of a recording, insurance or other plan of conducting business.

60 I claim:

1. A title document for motor vehicles providing in permanent consecutive form evidence of the chain of title and adapted for retention by the owner and direct transfer to each successive purchaser or trans-

feree, comprising permanently connected successive transfer record forms, and separably attached successive duplicate transfer record forms, each corresponding to one of the permanent transfer forms, separably attached lien notices and separably attached lien discharge notices corresponding to the individual lien notices, said notices being adapted for forwarding to the recording agency.

2. A title document for motor vehicles providing in permanent consecutive form evidence of the chain of title and adapted for retention by the owner and direct transfer to each successive purchaser or transferee, comprising permanently connected successive transfer record forms, and separably attached successive duplicate transfer record forms, each corresponding to one of the permanent transfer forms, separably attached lien notices and separably attached lien discharge notices corresponding to the individual lien notices, said notices being adapted for forwarding to the recording agency, the transfer forms being provided with properly designated spaces for entry of liens and discharges with definite reference to the lien and lien discharge notices.

3. A title document for motor vehicles providing in permanent consecutive form evidence of the chain of title and adapted for retention by the owner and direct transfer to each successive purchaser or transferee, comprising a permanently connected certificate of title to the original purchaser, 95 permanently connected successive transfer record forms, and separably attached successive duplicate transfer record forms each corresponding to one of the permanent transfer forms, in combination with originally 100 separate title certificates corresponding to the permanent transfer record forms and adapted to be attached thereto after issuance by the recording office in accordance with the corresponding duplicate transfer 110 form.

4. A permanent consecutive motor vehicle title record document designed for retention by the owner of the vehicle and immediate transfer to successive purchasers, consisting of permanently connected sheets, one sheet carrying permanently connected consecutive printed forms including a form of certificate of title to the original purchaser and forms of records of transfer to subsequent purchasers, another sheet having separable duplicate transfer record forms corresponding substantially to the permanent transfer forms, in combination with originally separate title certificates for subsequent purchasers adapted to be attached to individual permanent transfer forms.

5. A permanent consecutive motor vehicle title record document designed for retention by the owner of the vehicle and immediate 130

transfer to successive purchasers, consisting of permanently connected sheets, one sheet carrying permanently - connected printed forms including a form of certificate of title for the original purchaser and forms of records of transfer to subsequent purchasers, another sheet having separable duplicate record forms corresponding substantially to the permanent transfer forms, and another sheet having separable lien and lien discharge notice forms, in combination with originally separate title certificates for subsequent purchasers adapted to be attached to individual permanent transfer forms.

Signed at New York city in the county of New York and State of New York, this 13th day of May, A. D. 1921.

CARL C. CHASE.
